UNITED STATES PATENT OFFICE.

DAVID J. ROWLAND, OF YOUNGSTOWN, OHIO.

ADDING-MACHINE.

SPECIFICATION forming part of Letters Patent No. 447,363, dated March 3, 1891.

Application filed March 17, 1890. Serial No. 344,194. (No model.)

To all whom it may concern:

Be it known that I, DAVID J. ROWLAND, a citizen of the United States, residing at Youngstown, in the county of Mahoning and State of Ohio, have invented certain new and useful Improvements in Adding-Machines; and I do hereby declare the following to be a full, clear, and exact description of the invention, such as will enable others skilled in the art to which it pertains to make and use the same, reference being had to the accompanying drawings, which form a part of this specification.

My invention relates to an improved adding or calculating machine; and it consists in certain details of construction and combination of parts, as will be fully described hereinafter.

In the accompanying drawings, Figure 1 is a side elevation of my improved machine, which is constructed in accordance with my invention. Fig. 2 is a front elevation of the same, having a part of the disk and levers taken away the better to show the working parts. Fig. 3 is a plan view. Fig. 4 is a reduced front view of the entire machine, showing a disk for adding hundreds.

To construct a machine in accordance with my invention, I provide a base-plate *a*, having a strong standard *b* formed integral therewith for the purpose of carrying a short shaft *c*. This shaft *c* is rigidly secured to the said standard *b* and is provided at its forward end with a disk *d*, actuated by a flat coil-spring *e*, the form of which is indicated by dotted lines in Fig. 2, while in Figs. 1 and 3 the spring is shown in side view by full lines, one end of which spring is secured to the shaft *c* and the other to the said disk *d*. Pivoted beneath this disk *d* is an outwardly-projecting leaf or table *f*, having an upwardly-extending arm *g*, which is loosely connected to the shaft *c* in a manner that the said arm *g* may have a short movement toward or away from the disk *d*. At the rear of the arm *g* is a graduated check-lever *h*, which is loosely fitted to the shaft *c* and provided with or attached to a helical spring *i* in a manner that the said lever *h* will move toward the disk *d* when the front arm *g* is removed, and also bring the lever *h* back against a check-pin *j*, or to its normal position, when the same has been revolved by

the disk *d*. At the outer extremity of this lever *h* is a small pin *k*, adapted to engage in perforations *l*, formed about the periphery of the disk *d*. Projecting from the vertical arm *g* is a small bar *m*, provided with a return-point *s*, which engages with the perforations *l* at the front of the disk. Pivoted to the shaft *o*, which carries the table or leaf *f*, are a series of operating-levers *n*, provided with keys *p*, each of which has an upward extension *q* of the same vertical height or length, and the upper extremity of each vertical extension *q* remains out of or to the rear of the vertical plane of the lever *h* unless one of the keys *p* is depressed.

At Fig. 4 I have shown, in addition to the above-described machine, an extra dial *w*, loosely mounted on a stationary stud and having a ratchet formed about its periphery, which is adapted to engage with a projection *x*, formed on the disk *d*, at each revolution.

In operation the disk *d* is divided or separated into spaces about its front periphery and a pointer *v* secured to the forward end of the shaft *c*. To add a column of figures it is only necessary to press the keys *p* representing or corresponding with the said figures and the sum will be indicated on the disk *d* by the pointer *v*. If the fifth key is depressed, the same will move the table or leaf *f* downward, and in so doing release the pin *s* from the perforations *l* at the bottom of the disk *d* and engage the pin *k*, secured at the outer extremity of the lever *h*. (See Fig. 1.) The key marked 5, being depressed, moves its upper extension *q* beneath or into the same vertical plane as the fifth notch on the lever *h*. The disk *d*, being released from the pin *s*, revolves about the shaft *c* by the action of the spring *e* until stopped by the upward extension *q* of the fifth key, as the pin *k* on the lever *h* secures the same to the disk *d* and is kept attached thereto until released by removing the pressure from the key *p*, at which time the helical spring *i* recovers or brings the said lever *h* back to its original position, and the pin *s*, again entering one of the perforations *l*, prevents the disk from further rotation. Thus any number of figures may be added by simply depressing the keys corresponding to the same. At each revolution of the disk *d* the projec-

tion *x* engages with one of the teeth of the ratchet formed on the dial *w* and revolves the said dial *w* a short distance, and thereby indicates such movement by the stationary pointer *y*. Each space on the small dial *w* represents the sum of one hundred, while the spaces on the large disk *d* represents one. This construction enables the operator to read hundreds on the small dial *w* and any fraction thereof on the large disk *d*.

Having thus described my invention, I claim—

1. The herein-described adding-machine, consisting of the disk *d*, loosely mounted on a shaft *c*, rigidly secured in suitable bearings, the lever *h*, attached to the said shaft *c* and having the notched edge, the leaf or table *f* and operating-levers *n q*, pivoted beneath the disk, the arm *g*, attached to the said leaf or table *f* and provided with a pin *s* to engage with perforations *l*, formed about the periphery of the disk *d*, and a spring *i* for operating the lever *h*, substantially as and for the purpose described.

2. In an adding-machine, the combination of a primary adding-disk having a series of apertures, a pivoted spring-pressed arm adapted to enter one of the apertures in said disk and having a series of notches, a series of keys, each provided with an upwardly-extending arm adapted to enter one of the notches in the pivoted arm, an apron arranged in the path of the series of keys and provided with an arm which normally locks the primary adding-disk in position, a spring for impelling the primary adding-disk in one direction when released from its locking-arm, and means for returning the notched pivoted arm to its normal position, substantially as described.

In testimony that I claim the foregoing I hereunto affix my signature this 27th day of January, A. D. 1890.

DAVID J. ROWLAND. [L. S.]

In presence of—

M. E. HARRISON,
J. A. HERRON.
